FIG. 1.

FIG. 2.

FIG. 3.

UNITED STATES PATENT OFFICE.

ALLAN B. ELLIS, OF APPLETON, WISCONSIN.

BLACKBOARD OR SLATE.

1,387,534.

Specification of Letters Patent. Patented Aug. 16, 1921.

Application filed July 30, 1920. Serial No. 400,161.

To all whom it may concern:

Be it known that I, ALLAN B. ELLIS, a citizen of the United States of America, residing at Appleton, in the county of Outagamie and State of Wisconsin, have invented certain new and useful Improvements in Blackboards or Slates, of which the following is a specification.

This invention relates to new and useful improvements in blackboards and slates and has for its primary object to provide a novel construction of device wherein parallel lines equi-distantly spaced may be drawn upon the board in horizontal and vertical directions to provide block spaces for purposes of enlarging drawings or pictures.

A further object of the invention is to provide a blackboard or slate device combined with a novel type of ruler, the frame of the device and the ruler having coöperating parts to hold the ruler rigidly positioned during the act of drawing a line, these coöperating devices carried by the frame being so positioned to permit the drawing of a line at each side edge of the ruler with all of the lines equi-distantly positioned.

With the above and other objects in view, the present invention consists in the novel form, combination and arrangement of parts hereinafter more fully described in connection with the accompanying drawings, wherein like reference characters indicate similar parts throughout the several views.

In the drawings,

Figure 1 is a top plan view of a blackboard or slate constructed in accordance with the present invention, with the coöperating ruler operatively arranged thereon,

Fig. 2 is a cross sectional view taken on line II—II of Fig. 1 showing the pins at the end of the ruler received in the openings in the frame of the device, and

Fig. 3 is a perspective view of the ruler.

Briefly described, the present invention aims to provide a novel form of blackboard or slate which will be hereinafter referred to as a blackboard embodying a rectangular frame having an ordinary writing plate section carried thereby. The side faces of the frame strips are provided with openings extending therethrough and arranged equal distances apart. A novel type of ruler is associated with the blackboard and embodies an intermediate section that engages

the writing plate of the blackboard with the lower edge faces thereof cut away to provide clearance spaces for the side frames of the blackboard and to overlie the same while pins are carried by the ends of the ruler and are selectively positioned in the openings in the blackboard frame. The ruler is of a width equal to one-half the distance between two adjacent openings so that when the pins centrally depending from the ends of the ruler are received in an opening, a line may be drawn at each straight side edge thereof so that upon a change of position of the ruler with the drawing of subsequent lines, all of the lines will be equi-distantly spaced. In a similar manner, the ruler is positioned vertically upon the blackboard and cross lines may be drawn as desired.

Referring more in detail to the accompanying drawing, there is illustrated a blackboard of rectangular formation embodying side strips 4 having miter joints 5 at the meeting ends thereof and secured together in any suitable manner. As shown in Fig. 2, the lower inner edge of each strip 4 is grooved as at 6 to provide a pocket for the rectangular writing plate member 7 that may be adhesively, frictionally, or otherwise secured therein. As shown in Fig. 1, the side strips 4 are provided with equi-distantly spaced alined openings 8 extending therethrough, the corresponding openings at the opposed sides of the blackboard being alined and parallel with the two other opposite side strips.

The type of ruler employed with this blackboard is shown in detail in Figs. 2 and 3, the same embodying an elongated body 9, rectangular in shape and having opposite straight edges 9'. The lower faces of the opposite ends of the ruler 9 are cut away as at 10 to permit the lower face of the ruler 9 to engage the upper surface of the writing plate 7 as shown in Fig. 2, the ruler being cut away for a distance inwardly of each end to permit the inner walls 10' of the cut away portions to substantially frictionally engage the inner edges of the side strips 4 and when so positioned, the upper walls of the cut away portions engage the upper sides of the strips 4. A headed pin 11 depends from each end of the ruler 9 at the cut away portion thereof and a cap plate 12 is mounted upon the upper side of each end of the ruler to overlie the head of the

pin as shown in Fig. 2 to retain the same in position. The pins 11 are carried by the ruler 9 in oppositely alined strip openings 8 as shown in said figure.

5 From the above detailed description of the device, it is believed that the construction and operation thereof will at once be apparent, it being noted that the ruler 9 is of a width equal to one-half the distance between the two adjacent openings 8 so that when the pins 11 are received in alined openings at opposite sides of the blackboard frame, a line may be drawn at each straight edge 9' of the ruler and upon placing the 15 ruler in the next transversely alined pair of openings, the ruler is positioned whereby two additional lines may be drawn so that four lines with two applications of the ruler are arranged equal distances apart and in 20 parallelism.

In a similar manner, vertical lines may be drawn and with the block arrangement of lines on the writing plate or board 7, the enlargement or reduction of pictures and the 25 like may be accomplished in an obvious manner. Also, with the pin and opening connection between the blackboard and ruler, a positive grip between the two elements is provided so that slipping of the ruler will 30 be entirely eliminated and wearing of the

engaging parts practically eliminated in view of the pin entering the hole.

While there is herein shown and described the preferred embodiment of the invention, it is nevertheless to be understood that minor 35 changes may be made therein without departing from the spirit and scope of the invention as hereinafter claimed.

What is claimed as new is:

The combination with a blackboard having a rectangular frame and equi-distantly spaced openings extending through the frame midway the edges at each side thereof, of a ruler having the opposite ends thereof cut away upon the lower face to provide 45 inner side shoulders substantially frictionally engaging the inner edges of the opposite sides of the blackboard frame, the upper walls of the cut away portions overlying the upper sides of the frame, and a pin depending from the end of the ruler into the cut away portion selectively received in transversely alined openings, the ruler being of a width equal to half the distance between two adjacent openings whereby two parallel lines 50 may be drawn at each mounting of the ruler with all of the lines equi-distantly spaced.

In testimony whereof I affix my signature.

ALLAN B. ELLIS.
